(57) CLAIM

The ornamental design for a table as shown and described.

DESCRIPTION

FIG. 1 is a perspective view of a table showing my new design;

FIG. 2 is a end elevational view, the opposite end being a mirror image thereof;

FIG. 3 is a side elevational view, the opposite side being a mirror image thereof;

FIG. 4 is a top view thereof; and,

FIG. 5 is a perspective view of my design, shown with optional trays as environmental elements and shown in dashed lines.

The fragmentary depiction of the surface pattern is understood to exist uniformly across those surfaces.

The bottom view of the table is not shown and forms no part of the claimed design. The dashed lines represent environmental elements only and form no part of the claimed design.
